INVENTOR

William Linhart.

BY
Howard C. Thompson

ATTORNEY

UNITED STATES PATENT OFFICE.

WILLIAM LINHART, OF NEW YORK, N. Y.

SINKER-FORMING MOLD.

Application filed March 1, 1924. Serial No. 696,124.

To all whom it may concern:

Be it known that I, WILLIAM LINHART, a citizen of the United States, and residing at New York, in the county of New York and State of New York, have invented certain new and useful Improvements in Sinker-Forming Molds, of which the following is a specification, such as will enable those skilled in the art to which it appertains to make and use the same.

This invention relates to devices for molding or casting sinkers such as used by fishermen, and particularly to a portable device of this class, and the object of the invention is to provide a molding tool which is so constructed as to permit of the molding or forming of sinkers of different sizes and weights, means being provided on the tool for indicating the respective sizes of the sinkers to be formed; and with this and other objects in view the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of a molding tool made according to my invention;

Fig. 2 is a section on the line 2—2 of Fig. 1; and,

Fig. 3 a perspective detail view of a sinker formed by the mold shown in Figs. 1 and 2.

In carrying my invention into effect, I provide a portable forming tool 5 which, in the construction shown, is fashioned to form a shank portion 6 provided at one end with a handle member 7 and at the free end of the shank 6 is an elongated conical mold body 8 substantially rectangular in form in cross section and which tapers downwardly and is closed at the bottom as shown at 9. The body 8 is provided with a mold chamber 10 which tapers inwardly and downwardly, and the shape of which is substantially rectangular in cross section the side and end walls of the chamber 10 being parallel in horizontal plane. The taper of the chamber 10 which opens outwardly through the top of the body 8 is sufficient to permit

of the removal of a molded member formed by the body 8 or the chamber 10 thereof.

Adjacent to the lower end of the body 8, the side walls thereof are provided with oppositely disposed apertures 11 which are tapered to receive a tapered pin 12, as clearly shown in Fig. 2 of the drawing, the pin 12 functioning as a core pin and forming an aperture 13 in the contracted end portion 14 of a sinker 15 as shown in Fig. 3 of the drawing.

The entire tool, if desired, may be composed of suitable metal, or the shank 6 and body 8 may be composed of metal and the handle portion 7 of insulating material, if desired, and in the use of the tool in the formation of a sinker of predetermined size and length, the core pin 12 is placed in position and the molten lead or other metal is poured into the chamber 10 of the body 8 to fill the chamber to a predetermined degree which may be represented on one side face of the body 8 by circular markings 16. In view of the fact that the body 8 is cold the molten metal will immediately be chilled and quickly set. By removing the core pin 12 the casting or molded member may be readily removed through the open end of the chamber 10. It is important that the walls of the chamber 10 be smooth and unobstructed to permit of the casting or molding of perfect sinkers and also to readily permit of the extraction or removal of the sinker when formed.

Instead of proceeding, as above set out, lead or other metal to be employed in the forming of sinkers may be weighed and dropped into the chamber 10 and the body 8 placed over a suitable flame or subjected to heat units to melt the lead or other molding metal, and in this way a sinker of proper size and weight may be formed.

It will be understood that my improved tool is designed particularly for use by fishermen or others to permit of the forming of sinkers of any size or weight to suit predetermined conditions, and by reason of the simplicity of the tool the same may be sold at a nominal expense within the means of the public in general.

It will be understood that while I have shown and described certain details of construction for carrying my invention into effect, I am not necessarily limited to these details, and various changes therein and modifications thereof may be made, within

the scope of the appended claims, without departing from the spirit of my invention or sacrificing its advantages.

Having fully described my invention, 5 what I claim as new and desire to secure by Letters Patent, is:—

1. A device of the class described comprising a body portion provided with a conical chamber, said body portion being provided 10 with a transverse aperture which opens into the contracted end portion of said chamber.
  2. A device of the class described comprising a body portion provided with a conical chamber, said body portion being provided 15 with a transverse aperture which opens into the contracted end portion of said chamber, and a core pin adapted to be mounted in said aperture.
  3. A device of the class described comprising a body portion provided with a conical chamber, said body portion being provided 20 with a transverse aperture which opens into the contracted end portion of said chamber, a core pin adapted to be mounted in said aperture, and said core pin and aperture being tapered.
  4. A sinker forming tool of the class described comprising a shank provided at one end with a handle member and the other end 25 of said shank being provided with an enlarged body portion provided with a conical chamber opening through one end of the body portion, and said body portion being provided with a transverse aperture adjacent to the contracted and closed end of said chamber.
  5. A sinker forming tool of the class de-
- scribed comprising a shank provided at one end with a handle member and the other end of said shank being provided with an 40 enlarged body portion provided with a conical chamber opening through one end of the body portion, said body portion being provided with a transverse aperture adjacent to the contracted and closed end of said chamber, and a core pin adapted to be mounted in said aperture to extend transversely through the contracted end portion of said chamber.
6. A sinker forming tool of the class described comprising a shank provided at one end with a handle member and the other end of said shank being provided with an 45 enlarged body portion provided with a conical chamber opening through one end of the body portion, said body portion being provided with a transverse aperture adjacent to the contracted end of said chamber, a core pin adapted to be mounted in said aperture to extend transversely through the contracted end portion of said chamber, and means on the body portion for designating the several sizes of sinkers to be formed.
7. A portable molding tool of the class described comprising a mold body having a substantially conical mold chamber therein, and a core piece adjacent the contracted end of said conical mold chamber and detachably mounted in said body.

In testimony that I claim the foregoing 70 as my invention I have signed my name this 28th day of Feb., 1924.

WILLIAM LINHART.
